SOOT BLOWER

Johann Schieffer, Oberhausen, Germany, assignor, by mesne assignments, to Diamond Power Specialty Corporation, Detroit, Mich., a corporation of Michigan

Application March 27, 1935, Serial No. 13,290
In Germany March 29, 1934

5 Claims. (Cl. 122—392)

This invention relates to a soot blower or fluid heater cleaner of the type in which a blower element is arranged to discharge cleaning fluid adjacent the parts of a fluid heater or the like 5 to be cleaned.

One of the primary objects of this invention is to provide a cleaner of the above mentioned character which will include a rotatable blower element and an improved stop mechanism for 10 limiting the rotative movement of the blower element.

A further object of the invention is to provide a stop mechanism of the above mentioned character which while being adapted to limit 15 the rotative movement of the blower element will nevertheless permit the blower element to be rotated through a full 360 degrees.

The invention contemplates further the provision of a blower element mounted for projecting and retracting movement and the provision 20 of an improved means for effecting these movements of the blower elements.

Numerous other objects and advantages of 25 this invention will become more apparent as the following description proceeds particularly when reference is had to the accompanying drawing wherein

Fig. 1 is a longitudinal sectional view through a soot blower constructed in accordance with the 30 teachings of this invention;

Fig. 2 is a vertical sectional view through the blower shown in Fig. 1; and

Fig. 3 is a fragmentary detail sectional view taken substantially on the lines 3—3 of Fig. 2.

35 Referring then particularly to the drawing wherein like reference characters designate corresponding parts throughout all views, the numeral 10 designates a wall of a fluid heater such for example, as a boiler, there being portions of the fluid heater such as tubes or the like not shown which are adapted to be cleaned by the discharge adjacent the same of cleaning fluid as will hereinafter be more fully apparent.

40 Mounted in an opening 11 in the wall 10 is a wall box 12 providing a passage 13 in which a blower nozzle 14 is mounted for rotative and longitudinal movement. The blower nozzle is secured by a nipple 15 to a tube 16 which is mounted for longitudinal movement on a tube 17. A 45 fluid tight joint is provided between the tubes 16 and 17 by the gland 18 and packing 19.

The pipe 17 is rigidly carried by the discharge end 25 of a gooseneck 26. This gooseneck forms a part of the blower head and is provided at its 55 inlet end 27 with a valve seat 28 controlled by

a valve 29. A suitable cleaning fluid supply pipe 30 is connected to the inlet end of the gooseneck for supplying cleaning fluid to the same. The valve 29 is provided with a stem 35 which carries at its end a flange 36 which is engaged by a 5 spring 37 which functions to normally hold the valve in closed position. A lever 38 pivoted as at 39 on a lug carried by the gooseneck has a portion 40 adapted to engage the valve stem 35 to move the valve to open position. The lever 38 has a free end 41 adapted to be engaged by a 10 suitable cam for actuating the lever and thus opening the valve as will hereinafter be more fully brought out.

Carried by the wall box 11 is a base plate 45 15 and secured to this base plate is a housing 46. The lower end of the gooseneck is bolted to the base plate as at 47, while the upper end of the gooseneck is secured to the housing 12 by means of a protecting cover 48. 20

Fixed to the outer end of the tube 16 is a collar 50 which carries a tooth or lug 51 for a purpose which will be later described. Secured to the collar 50 as by the pins 52 is a cam 53 which is adapted to engage the end 41 of the 25 lever 38 when the tube 16 is moved forwardly, or into the fluid heater by mechanism about to be described.

For a substantial portion of its length the outer 30 surface of the tube 16 is threaded as at 55. Additionally, the outer surface of this tube is provided with an annular groove 56 and a longitudinally extending key way 57. To prevent rotation of the tube 16 during its travel into the fluid heater, there is provided a key or lug 58 35 which is carried by the base plate 45 and which engages the key way 57. Journalled in the base plate 45 and in the housing 46 is the hub 60 of a gear 61. The interior of the hub 60 is provided with screw threads 62 arranged to engage 40 the screw threads 55 on the outer surface of tube 16 to effect a longitudinal movement of the tube 16 and thus the blower nozzle or element when the gear 61 is rotated relative to the tube 16. The arrangement is such that the tube 16 will be 45 advanced until the collar 50 contacts the edge of the hub 60, and to take up the end thrust on the hub 60 there is therefore provided the ball thrust bearings 63.

For rotating the gear 61 there is provided a 50 pinion 65 which is fixed to shaft 66, this shaft being suitably journalled in the housing 46 and base plate 45. Likewise fixed to shaft 66 is a gear 67 which meshes with a pinion 68 fixed to one end of a shaft 69. Fixed to the other end of shaft 55

69 is a sheave wheel 70 adapted to be rotated by a suitable chain 71.

For the purpose of limiting the rotative movement of the blower element while permitting rotation of the element through 360 degrees, the following structure is provided. Formed in the outer face of the housing 46 is a dove tailed groove 75. Secured in one end of this groove as by the pins 76 is a block 77 recessed as at 78 to receive a pawl 79. This pawl is pivotally mounted in the recess on the pin 80 and disposed in the recess is a spring 81 which normally urges the pawl outwardly. Fixed in the other end of the dove tailed groove as by the pins 84 is a block 85. This block 15 is provided with a socket which receives a spring 86 and this spring engages the adjacent end of a block 87 which is mounted for sliding movement in the dovetailed groove 75. The block 87 is recessed as at 88 to receive a pawl 89 which is pivoted in the recess as at 90. A spring 91 engages the inner face of pawl 89 and tends to urge the same outwardly.

In operation, it will be understood that normally, that is when the blower element is not in use, it is in its retracted position as shown in Fig. 1 of the drawing. The operation of the blower element consists in moving the same longitudinally until the discharge port 95 thereof is suitably located within the fluid heater to discharge cleaning fluid adjacent the portions thereof to be cleaned and in then rotating the blower element through a desired arc and in then retracting the blower element to its stored position.

This operation is effected by suitably pulling on 35 the chain 71 to rotate the sheave wheel 70 in a counter clockwise direction. This effects the rotation of gear 61 in a counter clockwise direction and the threads on the interior of the hub 60 of this gear engaging the threads 55 on the exterior 40 of tube 16 cause the tube 16 to travel to the right as viewed in Fig. 1 of the drawing. It will be understood that the gear 61 is so journalled as to be held against longitudinal movement while the tube 16 is prevented from rotating by virtue of 45 the engagement of key 58 in key way 57.

The axial movement or the projecting of the blower element continues until the key 58 registers with the circumferentially extending groove 56. At this instant the collar 50 abuts the outer 50 end of hub 60 while the cam 53 engages the free end 41 of lever 38 to open valve 29. It might be noted at this point that the cam 53 is circular or conical if the blower element is designed to blow through a complete 360 degrees rotation. 55 If on the other hand, it is desired that the blower element blow through a portion or portions only of its rotation, the cam 53 will be suitably designed to effect an opening and closing of valve 29 during rotation of the blower element.

60 The projecting of the blower element to the position where collar 50 abuts hub 60 causes the lug or tooth 51 to engage the outer face 96 of pawl 89 depressing this pawl against the force of spring 91. Continued counter clockwise rotation 65 of the sheave wheel and thus of the gear 61 causes the blower element to rotate in a counter clockwise direction with the gear 61, it being understood that this rotation of the blower element is permitted by virtue of the registering of key 58 with the circumferential groove 56. It will be further understood that when the collar 50 abuts hub 60 the hub and collar become locked together thus causing the tube 16 to rotate with the gear 70 75. Counter clockwise rotation of the blower ele-

ment causes the lug 51 to ride over the pawl 89 or to the left as viewed in Fig. 3 and then around the interior of the housing until it engages the outer face of pawl 79. The outer face of this pawl is provided with the cam surface 97 so that the lug 51 depresses the pawl 79 against the force exerted by the spring 81. Continued rotation of the blower element causes the side face of lug 51 to engage the end face 98 of pawl 89 moving this pawl and its block 87 to the left, as viewed 10 in Fig. 3, against the force exerted by the spring 86. The block 87 is mounted for sufficient movement to permit the blower element and the lug 51 to move through 360 degrees at which time further movement of the block 87 and thus of the 15 blower element is prevented by virtue of block 85.

When the blower element has been rotated through 360 degrees the lug 51 has been moved to a position where it clears the end of pawl 79 thus permitting this pawl to resume its normal 20 position and engage the adjacent face of the lug 51. Thus the lug is held fast between the two pawls 79 and 89 and further rotation of the blower element in either direction is prevented.

If now the sheave wheel is rotated in a clockwise direction, the gear 61 is rotated in the same direction causing the threads on the interior of the hub thereof to effect a longitudinal travel of the tube 16 and the blower element to their retracted position. It will be understood that longitudinal movement of the tube sufficient to move the tooth 51 from between pawls 79 and 89 will be also sufficient to cause the key 58 to again engage the key way 57. Thus continued clockwise rotation of the sheave wheel will effect a retracting 35 of the blower element to its original or normal position.

From the above it will be apparent that the invention provides a blower element mounted for rotation together with stop members one of which 40 is mounted for limited movement whereby the blower element may be rotated through a complete 360 degrees. More particularly, the stop mechanism includes one stop member rotatable with the blower element and another stop member carried by a relatively stationary part of the 45 boiler head.

Additionally, the stop members cooperate to so limit the rotation of the blower element that the key way 57 in the tube 16 is aligned with the 50 key 58 so that the blower element may be readily retracted after the blowing operation is completed.

When the blower element is projected, the cam 53 carried thereby engages the end of the lever 55 38 so as to control the actuation of the valve 29 upon rotation of the blower element. Thus any desired degree of blowing may be effected by properly constructing the cam 53.

If it is desired to cause the element to blow through a second 360 degree rotation, it is only necessary to retract tube 16 sufficiently to cause tooth 51 to clear pawl 89 thus permitting the pawl 89 and block 87 to return to their original positions shown in Fig. 3 of the drawing. Then the blower element may be rotated again in a counter clockwise direction through a second 360 degree rotation.

While the invention has been described with some detail, it is to be understood that the description is for the purposes of illustration only and is not definitive of the limits of the inventive idea. The right is reserved to make such changes in the details of construction and arrangement 70 75

of parts as will fall within a purview of the attached claims.

What I claim as my invention is:

1. In a soot blower, a blower element mounted for axial and rotative movement, means for effecting the axial and rotative movements of the blower element means for preventing rotation of said blower element during axial movement thereof, means providing for rotation of the blower element after a predetermined axial movement thereof and means for limiting the rotative movement of the blower element to bring the blower element into operative relation with respect to the means which prevents rotation of the blower element during the axial movement thereof.
2. In a soot blower, a blower element mounted for axial and rotative movement, means for effecting the axial and rotative movements of the blower element, a cooperating key and key way for preventing rotation of the blower element during axial movement thereof, means providing for rotative movement of the blower element after a predetermined axial movement thereof, and means for limiting the rotative movement of the blower element to align the said key and key way.
3. In a soot blower, a blower element mounted for axial and rotative movements, the outer surface of said blower element being threaded, a member mounted for rotation on said blower element and having threads engaging the threads on the blower element, means for rotating said member, means for preventing rotation of the blower element to effect an axial movement thereof upon rotation of said member, means providing for rotation of the blower element after a predetermined axial movement thereof, and means for limiting the rotative movement of the

blower element to bring the same into operative relation with respect to the means which prevents rotation of the blower element during axial movement thereof.

4. In a soot blower, a blower element mounted for axial and rotative movements, means including a key and key way for preventing rotation of the blower element during axial movement thereof, means providing for rotation of the blower element after a predetermined axial movement thereof, a single means for effecting the axial and rotative movements of the blower element, a stop rotatable with the blower element, and a pair of members fixed against rotation with the blower element and adapted to engage said stop after a predetermined rotative movement of the blower element to align the said key and key way.

5. In a soot blower, a blower nozzle mounted for axial and rotative movements, a tubular threaded member secured to said blower nozzle for movement with the same, a cleaning fluid supply tube on which said tubular threaded member is telescopically mounted, said tubular threaded member being provided with a longitudinally extending groove and with a circumferentially extending groove, a key engageable in the longitudinally extending groove to prevent rotation of the tubular threaded member during a portion of its axial movement, a gear threaded on said tubular threaded member and fixed against longitudinal movement, and means for rotating said gear to cause axial movement of said tubular threaded member and to then rotate said tubular threaded member and the blower nozzle when the key registers with the circumferential groove.

JOHANN SCHIEFFER.
